Attorney

UNITED STATES PATENT OFFICE.

THOMAS J. KEHOE, OF TOLEDO, OHIO, ASSIGNOR TO THE WILLYS-OVERLAND COMPANY,
OF TOLEDO, OHIO, A CORPORATION OF OHIO.

MOTOR-VEHICLE-DOOR HOLDER.

1,275,700.

Specification of Letters Patent. Patented Aug. 13, 1918.

Application filed April 22, 1916. Serial No. 92,833.

To all whom it may concern:

Be it known that I, THOMAS J. KEHOE, a citizen of the United States of America, residing at Toledo, Lucas county, Ohio, have 5 invented new and useful Motor-Vehicle-Door Holders, of which the following is a specification.

This invention relates to carriage door latches and particularly to latches for use 10 on motor vehicle doors.

The object of this invention is to provide a latch for carriage doors which is so constructed that the door will be firmly held in a closed position and prevented from 15 rattling when latched in the closed position.

A further object of the invention is to provide a latch for carriage doors which may be very easily and economically constructed, the principal parts of the latch being 20 stamped from sheet metal.

Further objects, and objects relating to economies of manufacture and details of construction will definitely appear from the detailed description to follow.

25 I accomplish the objects of my invention by the devices and means described in the following specification. My invention is clearly defined and pointed out in the appended claims.

30 Referring to the drawings:

Figure 1 is a side elevation with parts broken away of a motor vehicle body in which the device is incorporated;

Fig. 2 is a fragmentary sectional view of 35 the two members of the latch about to swing into coöperative relation;

Fig. 3 is a fragmentary perspective view of the latch member removed from the door;

Fig. 4 is a side elevation of the keeper 40 member; and

Fig. 5 is an enlarged detail sectional view showing the tapered wedge shaped projection of the keeper member locked in engagement with the wedge shaped recess of the 45 latch member by means of the latch bolt.

The motor vehicle body 1 is provided with the door jamb 2 and the door 3. Through the door 3 extends the bar 4 rockable by the handles 5 or 6. The latch member comprises a face plate 11, the upper end of 50 which is bent back at right angles at 10, to form a guide for the upper end of the latch bolt 9. The lower end 12 of the face plate extends in a plane parallel to the upper end 55 11, and between the portions 11 and 12 the

plate is struck in to form a tapered recess having lower and upper converging walls 13 and 15 and a rear wall 14, the edge of the door being recessed to accommodate these parts of the latch member. The upper wall 60 of the tapered recess thus formed has the flanges 16, 17 and 18 struck up therefrom to form guides for the head 19 of the latch bolt 9, the upper end of said latch bolt being guided in flange 10 as hereinbefore described. An arm 7 is rigidly carried out and extends from the rock bar 4, the other end of said arm being forked and engaging the reduced portion 8 of the latch bolt 9 above the guiding flange 10 so that the 70 rocking of the bar 4 will reciprocate the latch bolt. A spring 20 is disposed on the latch bolt 9 between the head thereof and the guide 10 and serves to hold the bolt normally projected. The keeper member is secured to the door jamb 2 in position to co-operate with the latch and comprises the upper and lower portions 21 and 22 which are parallel with each other and adapted to be secured to the edge of the door jamb, the 80 plate forming the keeper member being struck out between these upper and lower portions to form a tapered or wedge shaped projection having lower and upper converging walls 23 and 25 and a front wall 24, the 85 taper of such wedge shaped projection corresponding to the wedge shaped or tapered recess formed in the face plate of the latch member, so that when the door is closed, said recess engages the said projection snugly. 90 A notch 26 is provided in the upper wall 25 of the keeper member, in position to be engaged by the head 19 of the latch bolt to hold the members in latching engagement. The latch head 19 of the plunger may be 95 manually withdrawn by rocking a handle 5 or 6 against the action of the spring 20.

When the door is closed the wedge shaped or tapered recess formed in the face plate of the latch member moves into coöperative 100 relation with the tapered projection of the keeper member, and as these two members move relative to each other, the upper inclined wall 25 of the keeper member engages the head 19 of the latch bolt and presses back 10 the same against the tension of the spring 20 until the door is tightly closed, when the tapered projection of the keeper member is in snug engagement with the walls of the tapered recess of the latch member, and

the head 19 of the latch bolt 9 moves into place in the notch 26, so as to hold the parts in latching engagement and to prevent their moving relative to each other until the latch bolt is retracted by means of one of the handles 5 or 6.

It will be seen that when the door is latched, the extended surfaces of the walls 23 and 25 engage the walls 13 and 15 and the 10 action of the spring 20 upon the latch bolt tends to hold these surfaces in such engagement, with the result that vibration and rattling is effectively prevented by the use of this form of latch. It will also appear 15 that this latch is very simple, being composed of a few number of parts, and is of such a nature that it may be very easily constructed at a low cost, while at the same time it is especially efficient in operation.

20 What is claimed and it is desired to secure by United States Letters Patent is:

1. In a carriage door latch, the combination of a face plate having an inturned flange at its upper end, and having the central portion thereof struck in to form a wedge shaped recess, guide flanges struck up from the upper wall of said recess, a latch bolt moving parallel to said face plate with its upper end guided in said upper flange 25 and its head projecting through the upper wall of said recess and guided by the flanges thereon, means for reciprocating said latch bolt, and a keeper member adapted to be secured to the door jamb and having its central portion struck out to form a tapered 30 projection adapted to fit into the tapered recess of said face plate, the upper wall of said projection being provided with a notch 35 adapted to be engaged by the head of said 40 latch bolt.

2. In a carriage door latch, the combination of a face plate having a tapering recess, a latch bolt carried by said face plate

parallel thereto and projecting through the upper wall of said recess, means for reciprocating said latch bolt and a keeper member 45 adapted to be secured to the door jamb and having a tapering projection adapted to fit said tapering recess, the upper wall of said projection being provided with a notch 50 adapted to be engaged by the head of said latch bolt.

3. In a carriage door latch, the combination of a face plate having a recess tapering transversely thereof, a keeper member having a projection tapering transversely thereof and shaped to fit snugly in said tapering recess, a latch bolt carried by said face plate and movable parallel thereto into and out of engagement with said projection 60 on the keeper member.

4. In a carriage door latch, the combination of a keeper member adapted to be secured to the door jamb and provided with a projection having upper and lower converging walls, a plate adapted to be secured to the edge of the door and provided with a recess having upper and lower converging walls, said projection being adapted to snugly engage in said recess, the upper end of said 65 plate being inturned, a latch bolt slidably mounted in said inturned portion of the latch plate and having its head extending through and guided by the upper wall of said recess, the upper wall of said projection being provided with a notch engageable by the head of said latch bolt, a spring on said latch bolt disposed between the head thereof and the inturned portion of said latch plate, a rock bar extending transversely through 70 said door, an arm rigidly secured to said rock bar and provided with a forked end engaging the upper end of said latch bolt, and means for oscillating said rock bar.

In witness whereof I affix my signature. 85
THOMAS J. KEHOE.
